Primary Examiner—James Gandy*Assistant Examiner*—Robert M. Spear*Attorney, Agent, or Firm*—Banner & Witcoff, Ltd.[57] **CLAIM**

The ornamental design for a portion of a sheet of paper toweling, as shown and described.

DESCRIPTION

FIG. 1 is a plan view of a portion of a sheet of paper toweling showing our design, the bottom plan view being a mirror image thereof; and.

FIG. 2 is a plan view of a portion of a sheet of paper toweling showing a second embodiment of our new design, the bottom plan view being a mirror image thereof.

The sheet of paper toweling has no substantial thickness.

1 Claim, 1 Drawing Sheet

FIG. 1

FIG. 2
